CLAIM

The ornamental design for a phone case as shown and described.

DESCRIPTION

FIG. 1 is a top, front and right side perspective view of a phone case showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof showing the kickstand in an extended state; and,

FIG. 10 is a perspective view thereof showing the loop feature in an extended state.

The broken lines depict portions of the phone case that form no part of the claimed design.
